UNITED STATES PATENT OFFICE.

HUGH H. SCHRAMM, OF NEW YORK, N. Y.

RAIL-JOINT.

1,321,558.

Specification of Letters Patent.

Patented Nov. 11, 1919.

Application filed February 10, 1919. Serial No. 276,220.

To all whom it may concern:

Be it known that I, HUGH H. SCHRAMM, a citizen of the United States, and a resident of the city of New York, borough of 5 Manhattan, in the county and State of New York, have invented a new and Improved Rail-Joint, of which the following is a full, clear, and exact description.

The invention relates to an improved rail 10 joint with a self, or automatic, tightening and locking device and the object of this invention is to provide a simple and efficient device of this kind, comprising simple and practical features of construction.

15 Another object of the invention is to provide a device that is so constructed that it is easily applied and very difficult to remove or tamper with, and further it requires very little more attention after it is applied.

20 With these and other objects in view, the invention consists of certain novel features of construction as hereinafter shown and described and then specifically pointed out in the claim.

25 A practical embodiment of the invention is represented in the accompanying drawing forming part of this specification, in which similar characters of reference indicate corresponding parts in all the views.

30 Figure 1 is a perspective view showing a portion of the ends of the rails meeting and the outside fishplate of the rail joint attached and also the end of the inside fishplate of the rail joint.

35 Fig. 2 is a view of the ends of the two rails meeting with the holes for the studs, (or rivets).

In Fig. 3 are views showing the outside fish plate with A an end view, and B an 40 edge view.

In Fig. 4 are detailed views of the inside of the fishplate with the tightening and locking device.

Fig. 5 shows, side, end and edge views 45 of the inside plate.

The rail joint illustrated in Fig. 1 is provided with two fishplates, which are connected to each other by studs A⁵ passing through the holes 11 of the rails and the 50 apertures in the fishplates and are tightened and locked by the wedge or key 9 shown in Fig. 4, which gradually slides in between stud A⁵ and the back wall of the recess 10, by its own weight and the spring 6, as-55 sisted by the little movement and trembling

of the rails when the cars pass over them. As shown in Fig. 5 the inner fishplate is of the common form of construction with a series of studs A⁵, either fastened solid in the regular holes or passed through loosely 60 and with solid rivet heads on both ends of the stud, the latter not shown. This plate is secured to the inside, across the joint of the two abutting ends of the rails, by the studs 5 passing through the holes in the rails, which studs also connect the fishplate 3 on the opposite, outside, side of the rails through the corresponding holes or apertures in the plate which are sufficiently large to permit the stud heads to pass and from 65 these apertures extend longitudinal slots to fit the shanks of the studs 5 and by moving the studs into these slots the heads form shoulders abutting the side of the plate, thus preventing them from being withdrawn 70 without a backward movement. This fishplate 3 has a series of wedge or inclined surfaces extending from the large openings of the apertures to the ends of the longitudinal slots. This fishplate 3 is also formed 75 with an opening or recess 10 on the inner side of the plate facing the rail, this opening extending from the top of the plate downward to the bottom and from the rear or back wall of the aperture to the end of the longitudinal slots minus the diameter of 80 the shanks of the studs. This recess is open facing the rail, the rail effecting the closing wall when the plate is in position. In this recess is located the wedge shaped key 9 85 which extends from near the top of opening 10 downward to past stud 5 and from the back wall to past the opening and overlapping the longitudinal slot. In this recess between the rail head and the top of key 9 90 is the spring 6.

When the plates are in position and plate 3 is moved forward and the studs enter the longitudinal slots, the key 9 passes between the stud 5 and the back wall of the 100 opening 10 and acts as a wedge, and by the action of the spring, and its weight downward the key drives the stud 5 and the plate 3 in opposite directions. This action with the stud heads moving forward on the 105 inclined surfaces of the plate effect the tightening and the downward movement of the key at the same time constitutes the locking device of the invention. It will be noticed that when the key is in place and be- 110

comes active it is impossible to remove it or any of the parts without destroying the studs. This tightening and locking device can be applied either to one or more, or 5 all of the studs, so as to make it most effective. In practical fields the construction of the details may necessitate alteration falling within the scope of what is claimed.

Having thus described my invention, I 10 claim as new, and desire to secure by Letters Patent:—

In a rail joint the combination with the adjacent rail ends and a fishplate mounted on each side in supporting relation of said 15 rails, of a series of studs extending through the rails and the fishplates, one of the fishplates having a series of longitudinal slots to receive the shanks of the studs and to en-

gage the shoulders formed by the heads of the studs, said plate also being formed with 20 a series of wedge or inclined surfaces one containing each of the longitudinal slots, and a recess in said plate opposite the inclined surfaces, and a wedge key in said recess, between one end of the recess and one side of a stud to move the plate and the 25 studs longitudinally in opposite directions and retard any backward movement, and a spring in the recess between the head of the rail and top of the wedge key. 30

In testimony whereof I affix my signature, in presence of two witnesses.

H. H. SCHRAMM.
